United States Patent Office

Des. 215,897
Patented Nov. 4, 1969

215,897

DESK FILE

Virgil E. Aydelotte, Fresno, Calif., assignor to Lit-Ning
Products Company, a corporation of California

Filed Sept. 23, 1968, Ser. No. 13,654

Term of patent 14 years

Int. Cl. D19—99

U.S. Cl. D74—2

FIG.1

FIG.2

FIG.3

FIG.4

FIG.5

FIG. 1 is a perspective view of a desk file in accordance with my new design, showing the front, right side and top thereof;

FIG. 2 is a front elevation of the desk file of FIG. 1;

FIG. 3 is a side elevation of the desk file of FIG. 1;

FIG. 4 is a rear elevation of the desk file of FIG. 1;
and

FIG. 5 is a bottom view of the desk file of FIG. 1.

The desk file is shown broken away in FIGS. 1, 2, 3 and 5 to indicate indefinite length.

I claim:

The ornamental design for a desk file, as shown and described.
